UNITED STATES PATENT OFFICE.

FREDERICK MAX PORITZ, OF NEW YORK, N. Y., ASSIGNOR TO STAR CHANDELIER COMPANY, OF NEW YORK, N. Y., A CORPORATION OF NEW YORK.

DESIGN FOR A CEILING CHANDELIER.

Application filed November 11, 1922. Serial No. 4,254. Term of patent 3½ years.

To all whom it may concern:

Be it known that I, FREDERICK MAX PORITZ, citizen of Germany, residing in New York, in the county of New York and State of New York, have invented a new, original, and ornamental Design Patent of a Ceiling Chandelier, of which the following is a specification, reference being had to the accompanying drawing, forming part thereof.

The figure is a plan view of a chandelier, showing my new design.

I claim:—

The ornamental design for a ceiling chandelier, as shown.

FREDERICK MAX PORITZ.
